HAND DRILL

David Staub, 9% Concept, Inc., Airport Station,
St. Petersburg, Fla. 33732

Filed May 21, 1969, Ser. No. 17,267

Term of patent 14 years

Int. Cl. D8—02

U.S. Cl. D8—61

FIG. 1

FIG. 2

FIG. 3

FIG. 4

FIG. 1 is a perspective view of a hand drill showing my new design;

FIG. 2 is a side elevational view;

FIG. 3 is a rear end view; and

FIG. 4 is a front end view.

The broken line showing of a bit is for illustrative purposes only.

I claim:

The ornamental design for a hand drill, as shown and described.
